[57] CLAIM

The ornamental design for a film scanner, as shown and described.

DESCRIPTION

FIG. 1 is a front, top and right side view of a film scanner showing our new design, with the film cartridge chamber access door closed;

FIG. 2 is a front elevational view thereof;

FIG. 3 is a top plan view thereof;

FIG. 4 is a bottom plan view thereof;

FIG. 5 is a right-side elevation view thereof;

FIG. 6 is a left-side elevation view thereof; and,

FIG. 7 is a front, top, right-side perspective view thereof with film cartridge chamber access door open.

The broken lines of the case for insertion into a desktop computer bay in FIGS. 1 and 3-7 are for illustrative purposes only and form no part of the claimed design.
